TAPE APPLICATOR

Elmer Clampitt, Indianapolis, Ind.

Application May 17, 1950, Serial No. 162,582

1 Claim. (Cl. 216—33)

1

This invention relates to a device for holding and applying sealing tape having one side thereof tacky in nature so as to provide an adhesive surface without the use of water or any other medium, whereby the tape may be caused to adhere to any desired surface simply by applying it thereto and pressing it down thereon. Heretofore, such devices commonly known as applicators have not been entirely too successful in view of the fact that the tape had to be handled by the operator's fingers at one or more steps in applying the tape to a surface, so that the operator's fingers became wrapped by the tape itself so that some of the tape had to be lost in getting the tape initially applied to the surface before stringing it out thereover.

The present invention includes the very essential step of gripping the tape from the adhesive side against a pressure roller so that the operator's fingers do not at any time have to come into contact with the adhesive side of the tape except perhaps when the device is to be loaded. However the fingers are entirely removed from contact with that adhesive side during the applying steps.

The invention is intended to utilize the commercially obtainable rolls of ribbon-like material in the nature of a tape, wherein therein there is a temporary adhesion between successive layers of the tape in the roll which will prevent the tape normally from unrolling except when an end portion thereof is pulled from the roll. The tape is not adhesive on one side and has the adhesive surface on the other side, this other side being normally the inner side of the tape as it is found in the roll form.

The primary objects and advantages of the invention reside in the provision of a structure into which one roll at a time of the tape material may be inserted to be revoluble therein as an end portion may be pulled from the roll, and further in the provision of a finger like member contacting the adhesive side of the tape to hold it against a pressure roll utilized in pressing the tape onto the surface which is intended to receive the tape.

These primary objects and advantages of the invention further include the provision of an exceedingly simple and economically produced carrier which also provides a tape cutting-off means without having to hold the roll, and without the operator having to grip the roll of tape in any manner.

These and many other objects and advantages of the invention will become apparent in the

2

following description of two of the best forms as now known to me, as illustrated in the accompanying drawings, in which

Fig. 1 is a view in side elevation of a structure embodying the invention;

Fig. 2 is a view in front end elevation;

Fig. 3 is a view in bottom plan;

Fig. 4 is a view in top plan;

Fig. 5 is a view of a modified form of the invention on an enlarged scale;

Fig. 6 is a view in front elevation;

Fig. 7 is a view in bottom plan;

Fig. 8 is a view in vertical transverse section on the line 8—8 in Fig. 5; and

Fig. 9 is a view in detail on a further enlarged scale on the line 9—9 in Fig. 6.

Referring first to that form illustrated in Figs. 1—4, now I form a body 10 to be generally arcuate in shape, and turning rearwardly to carry a suitable handle 11. On the forward portion of the body 10, there is mounted a U-shaped member generally designated by the numeral 12, which straddles the body 10 from the underside to have two upwardly extending arms 13 and 14 so that the web portion 15 of the member 12 is brought into abutment against the under face of the forward portion of the body 10 and there secured in a fixed manner by any suitable means such as by rivets 16.

Each of these upturned arms 13 and 14 carry a slot 17 entering from the rear side and inclined downwardly and forwardly therefrom. A cylindrical core 18 is provided to have the core 18 revolubly supported by a central rod 19 extending therethrough to have its ends rest in the inner lower ends of the slots 17. Thus it is to be seen that the core 18 is removable from between the arms 13 and 14 simply by lifting it upwardly and rearwardly. Preferably these arms 13 and 14

yieldingly extend inwardly one toward the other so that they have to be pressed apart to receive the core 18 therebetween.

A roll of tape 20 is generally provided as obtained in the market with a core 21 having an opening therethrough into which the core 18 is snugly receivable. The roll 20 is thus mounted on the core 18 and carried between the arms 13 and 14. Preferably a spring member 22 is fixed by its lower end 23 to the top side of the body 10, and is curved around rearwardly and upwardly, and thence forwardly, to normally press downwardly by a free end portion 24 against the roll of tape 20. The surface of the roll exposed externally is of the smooth, non-adhesive type.

Thus if an end portion 25 is pulled from the roll

20, the side A will be non-tacky while the side B will be the tacky side.

A flat bar of metal 26 is carried forwardly from the leg 14 to a distance ahead of the forward end of the body 10, and is bent thence substantially at a right angle thereto to form a front cross bar section 27, substantially of a length equal to the width of the body 10, and is then bent rearwardly by a portion 28 which terminates by a diagonally cut end portion 29. This end 29 is in parallelism with an edge 30 provided on a forwardly extending side bar 31, extending forwardly from the lower end of the leg 13. The spacing between the edge 29 and the edge 30 is made to be such that the tape end portion 25 may be inserted laterally therethrough to come under a pressure roller 32 which is mounted on an axle 33 carried by its ends through the bar 26 and the end portion 28. This roller 32 while not necessarily so, is preferably made out of a rubber-like material so as to be slightly resilient.

On the under side of the web 15 there is secured a finger 33 which is directed toward the roller 32 and has a pointed end 34 which is spaced from the roller 32 just that distance which would cause it to contact the tacky side of the tape end portion 25 and hold it against the roller 32. There may be a slight pressure between that finger end 34 and the tape end 25 to cause it to be snugly positioned against the roller 32. In other words there is no tendency of the tape 25 to be free from the roller 32 in that zone of contact by the finger 34.

The tape end portion 25 is positioned as just described and as illustrated in Fig. 1, so that the tape may then be applied to any desired surface simply by pulling the handle 11 to the left, with the roller 32 pressing down on the tape 25 to press it against that surface. Then when the desired length of tape has been so applied, the handle 11 may be lifted while the roller 32 remains in compressive contact against the tape 25 and in a position to press the tape 25 against that surface until a cutting knife 64 comes into contact with the tape 25 and thereupon, the handle 11 may be twisted and lifted slightly to either side to cause the tape to be cut off thereby. As indicated, Fig. 2, this knife 64 is preferably of a serrated nature, and is mounted on the cross bar portion 27 to extend slightly therebelow, but normally up out of contact with the tape 25 when the tape is being applied to its surface intended to receive it.

The operator grips the handle 11, and may press the spring 22 forwardly toward the roller 20 in order to hold that roller 20 against rotation when the tape 25 is being cut off, or during the applying operation if so desired. The spring 22 primarily is employed to retain the roll of tape 20 in its position between the arms 13 and 14 so it does not tend to rise and be lifted therefrom.

Referring now to that form of the invention as illustrated in Figs. 5-9, this form is primarily intended to be of a type which may be readily held in the palm of an operator's hand, it being understood that the size of the structure as shown in the drawing is of an exaggerated size.

In this form, there is a receptacle 35 generally of a cup-like nature. It consists of the side wall 36 having an annular wall 37 extending therefrom. The central portion of the wall 36 is pressed inwardly to form a thimble 38 around the circumferential portion of which there may be received a hollow core 21 of the roll of tape 20. A retaining cover 39 is formed to be circular in shape to extend over the wall 37 to seat there-

against, and further to have an inwardly extending central thimble 40 which may enter the hollow core 21 of the roll 20 as indicated in Fig. 8. In other words the circumferential portions of the thimbles 38 and 40 form bearing surfaces around which the roll of tape 20 may turn.

To the thimble 38, centrally thereof, is fixed a post 41 into which screw-threadedly engages a screw member 42 in turn preferably fixed centrally of the thimble 40, so that the cover 39 may be positioned over the cup 35 simply by bringing the two members together and having the screw member 42 turned into screw-threaded engagement with the member 41 by revolving the cover 39.

The annular wall 37 is continued in a tangential section 42 in one zone of the cup 35 relatively downwardly to a lower edge 43 which is carried inwardly therefrom and at right angles thereto, and slightly above a tangential foot portion 48. This straight wall length 42 is united to an extended side section 44 integral with the wall 36, and from the opposite side of the section 42, there is turned around in parallel relation to the portion 44 a flange 45 which has its upper edge cut in an arcuate manner to conform to the curvature of the cover 39, Fig. 5. Between the lower end portion of this flange 45, and the extended wall portion 44, is revolvably carried a pressure roller 46 on an axle 47 mounted in close proximity to the lower edge 43.

The wall portion 48 terminates primarily back a distance from the roller 46, by an edge 50, and is provided with an integral tongue 49 extending centrally from the terminal edge 50 to be directed toward the surface of the roller 46, in such manner that the end portion 25 of the tape coming from the roll 20 will be held firmly against the roller 46. The tongue 49 terminates in a point 51 which is in actual contact with the tacky side of the tape 25. The flange 45 terminates by a relatively rear vertical edge 52, and there is an upturned flange 53 from the portion 48 terminating by a vertical edge 54. There is a space left between the two vertical edges 52 and 54 so that the end portion 25 from the roll of tape 20 may be manipulated between the roller 46 and the tongue point 51 when the cup 35 is initially loaded with the tape 20.

The wall portion 42 is provided with a pressed outwardly band 55 so that a cut-off knife 56 may have an upper portion 57 thereof frictionally carried across the front face of that wall portion 42 and under the band 55 and thence on up by a short length thereabove so as to be retained thereby. The knife 56 is preferably provided with an under serrated edge 67, and there is an outwardly springing tongue 58 bearing against the under edge of the band 55 so as to hold the knife 56 in a fixed position of elevation in respect to upward pressure.

To use this form of structure thus described in regard to Figs. 5-9, the cup 35 having been loaded with the roll 20 and the cover 39 placed in its closed position as indicated in the drawing, is held in the palm of the operator's hand, to have the end portion 25 pressed down on the surface to which the tape is to be applied, by pushing the roller 46 thereagainst, whereupon the device is pulled thereaway from the initial zone of contact, until the desired length of tape 25 has been pulled outwardly and pressed down onto that surface, whereupon the entire device is rocked over until the edge 67 of the knife 56 is brought into contact with the tape, and then the

device is given a slight twist to one side to cause the edge 67 to sever the tape.

While I have herein shown and described my invention in the two specific forms, it is obvious that structural changes may be employed without departing from the spirit of the invention, and I therefore do not desire to be limited to those precise forms beyond the limitations which may be imposed by the following claim.

I claim:

An applicator to apply a pressure-sensitive adhesive tape from a contained roll, one side of the tape having a sensitive, tacky adhesive side, and the other side being non-sensitive and non-adhesive, comprising a tape roll carrier having a 15 presser foot portion, and a front wall portion disposed vertically to said foot portion with an opening through the foot portion adjacent the front wall, both said foot and said front wall being spaced from said roll and being tangential 20 thereto to be at substantially right angles one with the other; side walls extending between said foot portion and said front wall; a pressure roller revolvably carried by and between said side walls to have an under side peripheral portion below 25

the plane of said foot portion; said tape being carried by its non-sensitive side around the under side of said roller; and a substantially rigid, pointed tongue extending integrally from said foot portion in substantially the same plane thereof, forwardly to contact the pressure-sensitive side of said tape by a point to hold the tape compressibly against said roller; and a tape cut-off knife carried at the lower end of said front wall, forwardly of said roller at an elevation approximately that of said tongue point.

ELMER CLAMPITT.
